UNITED STATES PATENT OFFICE.

ISIDOR ROSENBLATT, OF NEW YORK, N. Y.

DESIGN FOR A CHANDELIER OR ANALOGOUS ARTICLE.

Application filed November 5, 1927. Serial No. 24,026. Term of patent 3½ years.

To all whom it may concern:

Be it known that I, ISIDOR ROSENBLATT, a citizen of the United States of America, and a resident of the city, county, and State of New York, have invented a new, original, and ornamental Design for a Chandelier or Analogous Article, of which the following is a specification, reference being had to the accompanying drawing, forming a part hereof.

The single figure of the drawing shows a front elevational view of the chandelier or analogous article.

I claim:

The ornamental design for a chandelier or analogous article substantially as shown.

ISIDOR ROSENBLATT.
